UNITED STATES PATENT OFFICE.

MICHAEL GLYNN, OF OTTERBEIN, INDIANA.

WIND-STACKER.

SPECIFICATION forming part of Letters Patent No. 700,760, dated May 27, 1902.

Application filed October 3, 1900. Serial No. 31,846. (No model.)

To all whom it may concern:

Be it known that I, MICHAEL GLYNN, a citizen of the United States, residing at Otterbein, in the county of Benton and State of Indiana, 5 have invented a certain new and useful Improvement in Wind-Stackers, of which the following is a specification.

My invention relates to the improvement of wind-stacker attachments for threshing-machines; and the objects of my invention are to provide the sectional stacker-tube with an extensible hood whereby said hood may be supported at different distances from the end of the stacker-tube, to so construct my 15 improved stacker as to control the deposit of the straw and chaff therefrom, to so construct the same as to prevent interference with the draft through the tube and thereby prevent the tube becoming choked with wet straw, to 20 admit of building the straw stack with a comparatively vertical rear side, to assist in toppling the stack against the wind, and to accomplish other objects the details of which will be set forth hereinafter. These objects 25 I accomplish in the manner illustrated in the accompanying drawings, in which—

Figure 1 is a side elevation of my improved stacker. Fig. 2 is a plan view of the same, and Fig. 3 is an enlarged section on line $x x$ 30 of Fig. 1.

Similar numerals refer to similar parts throughout the several views.

1 represents a portion of a separator-top, from which rises the inner section 2 of the 35 stacker-tube, this tube being adapted in the usual manner to receive and discharge the straw, chaff, &c., which is ordinarily blown therethrough by a fan contained within the machine. It is obvious that the stacker-tube, 40 may be formed of any desired number of telescoping sections; but for the purpose of illustrating my invention I have shown only the inner and outer sections 2 and 3, the section 3 sliding within the section 2 in the usual 45 manner. Loosely embracing the upper and rear portion of the section 2 is a yoke 4, the latter having extending forwardly therefrom, on opposite sides of the tube, rods 5, these rods extending loosely through outwardly 50 projecting keepers or eyes 6, which are formed with or secured on the outer sides of bands 7

and 8, which respectively embrace the outer ends of the tube-sections 2 and 3. Upon the upper side of the forward portion of the section 2 I support a pulley-carrying yoke or 55 bracket 9, within which are journaled pulleys 10 and 11. Upon the upper side of the yoke or arch 4 is supported a similar pulley-bracket 12, in which is journaled a pulley 13. Beyond the forward end of the tube-section 3 60 the rods 5 are connected by a yoke or upwardly-curved bridge 14. Pivotedly secured to the outer end portions of the rods 5 are the lower ends of a hood-bow or arch-strip 15, the sides of this bow having pivoted thereto rear 65 and forward bows 16 and 17. The bows 15, 16, and 17 have secured therein a hood of suitable woven material 18, which, as shown in the drawings, is adapted to extend below the bow 17. The bow 15 has connected thereto 70 with a downwardly-extending arm 19, which through the medium of a spring 20 is connected with one of the rods 5, the tension of said spring being such as to normally retain the hood in position opposite the end of the 75 tube-section 3, as shown in Fig. 1 of the drawings. Connected with the upper portion of the bracket 12 is one end of an operating-rope 21, this rope running from said bracket 12 forward over the pulley 10, back over the 80 pulley 13, thence forward and over the pulley 11, from which said rope runs to a bracket or standard 22, which rises from the separator-top in rear of the stacker-tube. The rope 21 may be detachably connected with 85 said bracket 22 in any desired manner.

Connected with the outer hood-bow 17 is an operating-cord 23, the latter extending over the hood and rearward to the bracket 22. As indicated at 24, I also provide a connection 90 between the top portions of the brackets 14 and 22, which connection may be in the nature of a rope, cable, or wire.

The manner of utilizing my improvements is as follows: It being desired to move the 95 hood forward it is evident that a pull upon the rope 21 will impart a forward movement to the yoke 4 and sliding rods 5, the latter moving loosely in the eyes 6 of the clamping-rings 7 and 8. It is obvious that this forward 100 sliding movement of the hood-rods is accomplished after sufficiently loosening the con-

necting rope or cable 24. By this operation of moving the hood forward it will be seen that said hood may be supported at such distance from the outer tube-section 3 as to prevent any interference with the draft through the stacker-tube and at the same time receive the straw and chaff and deflect the latter downward onto the stack without undesirable scattering of the same. It will be seen that the hood may be extended to a point above the rear wall of the stack and the hood so turned as to cause a substantially vertical deposit of the straw and chaff, so that the wall of the stack may be built comparatively straight and substantially vertical. It is obvious that by pulling inward on the cord 23 the outer or lower bow of the hood may be folded back, together with the material comprising the hood, so as to impart a different inclination to the hood, if desired. It will also be seen that the extensible hood herein shown and the separating and operating attachments therefor may be connected with any of the ordinary forms of sectional wind-stackers and that the ordinary hood, which for the sake of clearness is omitted in the drawings and which is usually supported from the outer end of the outer section 3, may be used for the purpose of deflecting and depositing the straw and chaff, or said hood may

be thrown upward out of the way, admitting of the hood 18 being utilized.

I am aware that sectional wind - stacker tubes have been employed heretofore and that the outer tube-section is ordinarily provided with the hinged deflecting-hood, and therefore do not claim, broadly, such construction.

Having now fully described my invention, what I claim, and desire to secure by Letters Patent, is—

In a wind-stack, the combination with the inclined stacker-tube comprising sections 2 and 3 one telescoping within the other, of rods 5 on opposite sides of said tube, a slideable yoke 4 on said rear section with which the rear ends of said rods are rigidly connected, said rods slidably supported in connection with both of said tubes, a yoke-frame 14 connecting the outer portions of said rods, a cord connecting the latter with a fixed frame 50 portion in rear of the inner tube-section, a hood-frame connected with the outer end portions of said rods and a hood connected therewith and means for imparting a sliding motion to said hood-supporting rods, substantially as specified.

MICHAEL GLYNN.
